UNITED STATES PATENT OFFICE.

EDWARD H. FRICKEY, OF ST. LOUIS, MISSOURI.

ADJUSTABLE MULTIPLE DISK AND SHREDDING HAMMER.

Application filed July 30, 1919, Serial No. 314,244. Renewed January 30, 1922. Serial No. 532,860.

To all whom it may concern:

Be it known that I, EDWARD H. FRICKEY, a citizen of the United States, and resident of St. Louis, Missouri, have invented certain new and useful Improvements in an Adjustable Multiple Disk and Shredding Hammer, of which the following is a specification.

This invention relates to improvements in an adjustable multiple disk and shredding hammer, and consists in a plurality of disks located on the shaft and spaced at intervals apart, each disk being provided with a plurality of apertures and arranged to register in proper alignment with each other, and hammers located between the disks and hingedly supported between the same by pins passing through the apertures.

A further object of my invention is to construct a mechanism which is used in conjunction with crushers in which material of various kinds is to be crushed into small particles, the improvement consisting of placing a plurality of perforated disks on the shaft and between said disks are pivotally mounted a plurality of hammers and the arrangement of the perforations are such that the hammers may be adjusted in order to bring the outer edge or contacting surface of the hammer on its peripheral radius as the contacting surface of the hammer becomes worn by constant use.

Another object of my invention is to construct the hammers in such a manner that as the contacting surface becomes worn, this worn surface can be ground down and the hammer removed and reversed and adjusted to the next aperture in the disk which is of a height sufficient to take up the ground off surface of the hammer, thus bringing the hammer in proper radius of contact at the same time utilizing a greater portion of the hammer and dispensing with waste.

Figure 1, is a side elevation of my invention showing the general structure of the hammer supporting head and the position of the hammers located therein.

Fig. 2, is an edge view of the same.

Fig. 3, is a detail side view of one of the hammers with a part broken away.

Fig. 4, is an enlarged detail view showing a pair of the hammers located between the supporting disk.

Fig. 5, is a sectional view showing the disk hammer head and the manner of supporting the hammers therein.

In referring to the drawings in general 6 indicates a shaft on which is mounted a plurality of disks 7, and these disks are spaced apart by spacing rings 8, and after the required amount of disks and spacing rings have been applied on the shaft and arranged to properly register one with the other they are properly connected and bound together by the pins, rivets, or bolts 9, which extend through the entire series.

Each of the disks 7 are provided with perforations 10, and are arranged in rows radiating on the curvilinear spear from near the center to near the periphery of the disk, the general position and location of the perforations being shown in Fig. 1, of the drawing.

Between these various disks are placed hammers 11, each of which when applied being of their normal length and are attached to the base series of the apertures as that indicated by the numeral 12 and are held in pivotal or hinged position by the pins 13, these hammers are arranged as that shown in Fig. 3, the two edges being cut away at intervals in the shaft or semi-circular curvilinear 14 and arranged opposite each other so that as the contacting edge 15 of the hammer becomes worn during its continuous operation, the hammers can be removed from their position between the disks and the worn edge ground off at an angle as that shown by the dotted lines 16, then the hammer is reversed when replacing the same between the disks and its opening or eye 17, inserted in the next aperture 18 formed in the disks which apertures are so arranged as to be sufficiently high to take up the wear and allow the point 19 to extend to the proper peripheral radius 20 which is shown by dotted lines in Fig. 1.

The contacting edge of the hammers are also slightly bent to one side as that indicated by the numeral 21, and these bent points of the hammers are arranged to alternate as that shown in Fig. 4, the bent edge of one hammer being to the right, the other to the left and so on with the entire series of hammers.

In Fig. 1, I show but 2 hammers in position, one of its original length and the other of its shortest length, these hammers are placed at suitable intervals apart throughout the disk and each hammer has a suitable swing and contact with stop pins 22 and 23. These pins are so arranged according

to the length of the hammer and when the hammer becomes ground down to its shortest length it contacts with the stop pins 24 and 25 and the movement of the hammer is limited as that shown by dotted lines in Fig. 1.

- The essential feature of this invention is to construct hammers that can be re-ground as the surface becomes worn and then to add-
10 just the same to take up the worn surface by adjusting the hammers between the disks; in this manner I find a great saving of ma-
terial and a proper adjustment of the series
15 of hammers so that their contacting or ham-
mering surface is at all times on a proper
peripheral radius. As the hammers are
ground down as they become worn this edge
is then bent to one side as that shown by dot-
ted lines in Fig. 4.
20 Having fully described my invention what
I claim is:
1. A device of the character described
having a pivoted hammer consisting of a
flat bar with recessed edges, said recesses
25 being arranged in staggered relation on the
opposite edges of said hammer.
2. A device of the character described
having a pivoted hammer consisting of a
flat bar with its opposite edges having stag-
30 gered recesses and its outer end being bent

to one side and having an inclined surface
between its opposite edges.

3. In a rotary beater the combination of
a pair of rotary disks each having openings
therein at different distances from its center, 35
and a beater pivoted to said disks; said
beater having flat sides and recessed opera-
tive edges with its outer end inclined forming
an upper contact edge.

4. A device of the character described, 40
having a pivoted hammer consisting of a
bar with recessed edges, said recesses being
arranged in staggered relation on opposite
edges of said hammer.

5. A device of the character described, 45
having a pivoted hammer consisting of a
bar with recessed edges, said recesses being
arranged in staggered relation on opposite
edges of said hammer, the outer end of the
hammer being open to one side and having 50
an inclined surface between its opposite
edges.

In testimony whereof, I have signed my
name to this specification, in presence of two
subscribing witnesses.

EDWARD H. FRICKEY.
